UNITED STATES PATENT OFFICE

2,077,570

RECEPTACLE

Vincent A. Lamare, Chicago, Ill.

Application March 7, 1936, Serial No. 67,565

8 Claims. (Cl. 229—6)

The present invention relates generally to receptacles. More particularly the invention relates to that type of receptacle which is adapted for use in mailing or shipping a small article and embodies an open top and open bottom compartment for the article and a top and bottom closure for the compartment.

One object of the invention is to provide a receptacle of this type which is formed of substantially rigid cardboard, consists of a plurality of superposed laminations, and is characterized by the fact that the intermediate laminations have aligned compartment-forming cutouts and the end laminations form respectively the top and bottom closures for the cutout-formed compartment.

Another object of the invention is to provide a mailing or shipping receptacle of the last-mentioned character which is formed of but a single piece of cardboard and in which the laminations are hinged together and are formed by scoring the cardboard transversely thereacross at equidistantly spaced points and then folding the cardboard piece so that it is of plaited or accordian formation and the laminations thereof are in superposed relation.

A further object of the invention is to provide a receptacle of the type and character under consideration which embodies simple and novel means for assisting the hinge portions between the laminations in holding or securing the laminations against lateral displacement one relatively to the other.

A still further object of the invention is to provide a receptacle for mailing or shipping purposes which is generally of new and improved construction and may be manufactured at a low and reasonable cost and in which rigidity and strength of design are combined with ease and quickness of assembly.

Other objects of the invention and the various advantages and characteristics of the present receptacle will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective showing a receptacle embodying the invention prior to folding of the laminations into superposed relation;

Figure 2 is a perspective showing the receptacle in its normal or assembled position and with the top closure thereof in its raised or open position to permit of access to the compartment;

Figure 3 is a perspective showing the receptacle in readiness for mailing or shipping and with a gummed strip extending transversely therearound so as to seal or hold in place the top and bottom closures;

Figure 4 is an enlarged vertical sectional view illustrating the manner in which the laminations are hinged together and the compartment is formed by the cutouts in the central portions of the intermediate laminations;

Figure 5 is a fragmentary perspective of a receptacle which constitutes a modified form of the invention and includes linings of adhesive on the contiguous faces of the laminations for securing the laminations together; and

Figure 6 is an enlarged vertical section of a receptacle which constitutes another modified form of the invention which is characterized by the fact that the laminations have interfitting ribs and grooves whereby they are locked against relative lateral or sidewise displacement.

The receptacle which is shown in Figures 1, 2, 3 and 4 of the drawing constitutes the preferred embodiment of the invention and is designed for use in mailing or shipping a small elongated article. It is formed of a single piece 7 of cardboard and consists of a plurality of superposed laminations 8, 9, 10, 11, 12 and 13. The cardboard piece from which the receptacle is formed is rectangular, as shown in Figure 1, and preferably is three-sixteenths of an inch in thickness. The laminations 8, 9, 10, 11, 12 and 13 are formed by forming transverse scores 14, 15, 16, 17 and 18 across the cardboard piece 7. These scores, as shown in Figure 1, extend from one side edge of the cardboard piece to the other and penetrate approximately one-half of the way through the piece 7. They are spaced equidistantly apart and permit the sheet to be folded in order to bring the laminations into superposed relation. The scores 14, 16 and 18 are formed in one side of the piece 7 of cardboard and the scores 15 and 17 are formed in the other side of the cardboard piece and in alternate relation with respect to the scores 14, 16 and 18. By forming the scores in this manner the sheet when folded has an accordian or plaited formation and the laminations are each connected at one side by a hinged formation to the superjacent lamination and by a hinged formation at the other side to the subjacent lamination.

By reason of the fact that 55

the cardboard sheet is rectangular and the scores are spaced equidistantly apart, the laminations are all the same as far as size is concerned. The intermediate laminations, that is the laminations 5 9, 10, 11 and 12, have central rectangular cutouts 19. These cutouts extend lengthwise of the intermediate laminations. They are equal in size and when the cardboard piece 7 is folded so as to bring the laminations into superposed relation 10 they register with one another as shown in Figure 4 and form a compartment 20 in the interior. This compartment has an open top and bottom and is adapted to receive the article which is to be mailed or shipped in the receptacle. The end 15 laminations 8 and 13 are imperforate and form respectively a top and a bottom closure for the compartment 20. When these two laminations are in their folded position they lap respectively the laminations 9 and 12 and close or seal the 20 compartment 20.

In addition to the laminations 8, 9, 10, 11, 12 and 13 the receptacle of Figures 1, 2, 3 and 4 comprises a strip 21. This strip is formed of paper and serves to hold or secure the laminations 25 of the receptacle in abutting relation during mailing or shipping of the receptacle. As shown in Figures 3 and 4 of the drawing, the strip 21 is adapted to be folded around the top, sides and bottom of the receptacle and forms 30 when in its operative position an enclosing or surrounding band. The inner face of the strip is provided with a facing 22 of water soluble adhesive or gum whereby it may be adhesively secured in place. The ends of the strip are adapt- 35 ed to overlap one another, as shown in Figure 4. The width of the strip is less than the length of the receptacle and as a result when the strip is wrapped into encircling or surrounding relation with respect to the laminations the ends of 40 the receptacle, as shown in Figure 3, project beyond the side edges of the strip. Because of this it is possible when it is desired to open the receptacle to insert a knife or cutting tool under the outer portion of the free or unhinged side 45 margin of the lamination 8 and then by drawing the knife or tool lengthwise from one end portion of said margin to the other to sever the strip transversely and thus free the lamination 8 so that it may be swung upwardly with respect to 50 the lamination 9 for compartment exposing purposes. To facilitate transverse severing of the strip 21, a line 23 of perforations is formed in the strip. This line is adapted when the strip 21 is applied to the receptacle to be aligned with 55 the unhinged side edge of the lamination 8 and facilitates severing or cutting of the strip. The outer face of the strip forms a surface on which the name and address of the sendee and also the name and return address of the sender may 60 be written.

The receptacle is assembled by folding the cardboard piece 7 along the scores 14, 15, 16, 17 and 18 into accordion or pleated formation to bring the laminations into superposed relation. 65 When the laminations are in such relation the cutouts of the intermediate laminations, as heretofore pointed out, form the compartment or body portion 20. When it is desired to seal the receptacle so as to place it in readiness for mailing or shipping purposes the compartment 20 is closed 70 by swinging the end laminations 8 and 13 into lapped relation with the adjoining intermediate laminations and the gummed sealing strip 21 is applied as illustrated in Figures 3 and 4. After 75 application of the strip the laminations are se-

curely held in abutting relation and the receptacle as a whole is firm and rigid.

The mailing or shipping receptacle of Figure 5 constitutes a modified form of the invention. This receptacle is similar in design and construction to that of Figures 1, 2, 3 and 4 with the exception that it employs facings 24 of adhesive material to secure the laminations thereof in abutting relation instead of a gummed sealing strip. The facings 24 are preferably formed of 10 rubber material which is nonadhesive except when brought into contact with like or the same material. The intermediate laminations have facings of the adhesive on both sides thereof and the end laminations have facings only on 15 their inner sides. The facings are so arranged that when the laminations are brought into superposed relation they adhere to one another and thus effect a complete seal of the receptacle. The facings are secured or united to the laminations 20 by suitable coatings of cement or other material.

The receptacle which is shown in Figure 6 constitutes another or second embodiment of the invention. It is the same in design and construction as the receptacle of Figures 1 to 4 with 25 the exception that each lamination is provided along one side margin thereof with an upstruck portion which forms a longitudinally extending groove 25 on its under face and a complementary rib 26 on its upper face. The ribs 26 fit within 30 the grooves 25 as shown in Figure 6 and form interlocking connections whereby the laminations are held or locked against relative lateral displacement.

The receptacles herein shown are extremely 35 simple as far as construction is concerned and may be manufactured at a low and reasonable cost.

Whereas in the three forms of receptacles herein shown each include six laminations it is to be 40 understood that more or less laminations may be used depending upon the desired depth of the article-receiving compartment.

It is also to be understood that the invention is not to be restricted to the details set forth since 45 these may be modified within the scope of the appended claims, without departing from the spirit and scope of the invention.

Having thus described the invention, what I 50 claim as new and desire to secure by Letters Patent is:

1. As a new article of manufacture, a receptacle for mailing or shipping purposes, formed of a single piece of comparatively thick substantially rigid cardboard and comprising a plurality of 55 superposed laminations hinged together at the sides thereof and formed by bending the cardboard piece into pleated or accordion formation, the intermediate laminations having centrally disposed aligned cutouts therein forming a compartment with an open top and bottom, and the end laminations being imperforate and serving as closures for the top and bottom of the compartment.

2. As a new article of manufacture, a receptacle for mailing or shipping purposes, formed of a rectangular piece of comparatively thick substantially rigid cardboard having equidistantly spaced transverse scores across both sides thereof and 70 the scores on one side arranged in alternate relation with the scores on the other side, and comprising a plurality of superposed laminations hinged together along the sides thereof and formed by bending the cardboard piece along the 75

5 scores into pleated or accordion formation, the intermediate laminations having centrally disposed aligned cutouts therein forming a compartment with an open top and bottom, and the end laminations being imperforate and serving as closures for the top and bottom of the compartment.

10 3. As a new article of manufacture, a receptacle for mailing or shipping purposes, comprising a group of superposed hinged laminations formed by bending a single piece of cardboard into pleated formation, having aligned compartment-forming cut outs in the intermediate laminations and the end laminations forming top and bottom closures for the compartment and also having adhesive coatings between the laminations for holding the latter in superposed relation.

15 4. As a new article of manufacture, a receptacle for mailing or shipping purposes, comprising a group of intermediate superposed cardboard laminations provided with interfitting rib and groove connections therebetween and having aligned cutouts therein forming a compartment with an open top and bottom, and imperforate end laminations abutting against the outermost intermediate laminations and serving as closures for the top and bottom of the compartment.

20 5. A blank adapted to form a mailing or shipping receptacle and comprising a rectangular piece of comparatively thick substantially rigid cardboard having equidistantly spaced transverse scores across both faces thereof and with the scores on one face in alternate relation with the scores on the other face and serving to form with the latter laminations of uniform size and also having similarly located cutouts of uniform size in the central portions of the intermediate laminations.

25 40 6. As a new article of manufacture, a receptacle for mailing or shipping purposes, formed of a single piece of comparatively thick substan-

tially rigid cardboard and comprising a plurality of superposed laminations hinged together at the sides thereof and formed by bending the cardboard piece into pleated or accordion formation, the intermediate laminations having centrally disposed aligned cutouts therein forming a compartment with an open top and bottom, the end laminations being imperforate serving as closures for the top and bottom of the compartment, and separate means for holding the laminations in superposed relation.

5 10 15 7. As a new article of manufacture, a receptacle for mailing or shipping purposes, formed of a single piece of comparatively thick substantially rigid cardboard and comprising a plurality of superposed laminations hinged together at the sides thereof and formed by bending the cardboard piece into pleated or accordion formation, the intermediate laminations having centrally disposed aligned cutouts therein forming a compartment with an open top and bottom, and the end laminations being imperforate and serving as closures for the top and bottom of the compartment, and a band extending around the superposed laminations to maintain them in said relation.

20 25 30 35 40 8. As a new article of manufacture, a receptacle for mailing or shipping purposes comprising a body portion formed of a single piece of comparatively thick substantially rigid cardboard composed of a plurality of superposed laminations hinged at the sides thereof and formed by bending the cardboard piece into pleated or accordion formation, and having centrally disposed aligned cutouts therein forming a compartment with an open top and bottom, imperforate laminations serving as closures for the top and bottom of the compartment, and means for holding the imperforate and body portion laminations in superposed relation.

VINCENT A. LAMARE.
